PRODUCTION OF LOW BOILING HYDROCARBONS

Filed Feb. 10, 1933

UNITED STATES PATENT OFFICE

2,087,268

PRODUCTION OF LOW BOILING HYDRO-CARBONS

Howard W. Sheldon, Haddonfield, N. J., assignor
to Houdry Process Corporation, Dover, Del.,
a corporation of Delaware

Application February 10, 1933, Serial No. 656,052

18 Claims. (Cl. 196—52)

This invention relates to the production of such products as benzine, gasoline, naphtha, kerosene and the like from higher boiling starting material such as crude petroleum, or fractions of the same, or oils from the destructive distillation of carbonaceous materials.

One object of the invention is to combine known methods of pyrolytic conversion of hydrocarbons with a catalytic process capable of continuous operation and in which the contact mass is preferably regenerated in situ, thereby to enhance certain advantages inherent in the processes which are combined. Other objects will be apparent from the detailed description which follows.

One concrete embodiment of the invention is illustrated diagrammatically in the single figure of the accompanying drawing.

The apparatus as disclosed comprises a catalytic system, indicated generally by reference character A, a pyrolytic system, indicated by B, and a viscosity breaking device C, all three adapted to be used in combination to secure a high combined yield of low boiling hydrocarbons, such as gasoline, with a good antiknock rating. The use of the viscosity breaker C, however, is optional, depending upon the type of starting material.

The catalytic system A conforms, in general, to that disclosed in the copending application of Eugene J. Houdry, Serial No. 610,567, filed May 11, 1932. It comprises a tubular heater 1a and two or more catalytic converters 2a containing catalytic material capable of making the desired conversion, such as a contact mass consisting of an activated hydrosilicate of aluminum, with or without the addition of active metal oxides, preferably in molded form, as disclosed, for example, in the copending application of Eugene J. Houdry, Serial No. 600,581, filed March 23, 1932, so as to be capable of regeneration in situ. The catalytic converters are arranged for alternate operation on stream and in regeneration, the vaporized products from heater 1a being fed thereto through a valved line 3a, at atmospheric or low superatmospheric pressure and at a temperature from 750° to 1000° F., while the converted products are discharged through a valved line 4a. The regenerating medium for the catalytic mass in converters 2a, which medium may be an oxidizing agent, such as air diluted if desired with steam or flue gas, may be admitted through a valved connection 5a, and the fumes carried away by valved connection 6a.

The pyrolytic system B may be of any known

or suitable type, either liquid or vapor phase, such as Dubbs, Cross, tube and tank, de Florez, etc., the one indicated merely for the purpose of illustration being suggestive of the Cross type, comprising a heater 1b and a reaction chamber 2b. The hydrocarbon vapors from heater 1b are fed to chamber 2b by a line 3b under pressure and at a temperature ranging from 850° to 1100° F., and the converted products are discharged through a valved line 4b.

The viscosity breaker may be of any suitable or known type, comprising a tubular heater 1c arranged to bring the material to be treated to a temperature of from 700° to 900° F., and having a discharge line 2c and a feed line 3c.

Two fractionating columns are used, namely 1a and 1b and, as hereinbefore indicated, the overhead or gasoline fractions from each may be blended together to provide a high yield of high quality motor fuel. Line 4a of the catalytic system discharges into fractionator 1a, as indicated in the drawing, and the converted products issue from the top thereof through a line 8a, to be condensed and stored or subjected to a further refining operation. The residual oil or recycle stock which is thrown down in fractionator 1a is conducted from the bottom thereof by line 5b as feed for heater 1b of the pyrolytic system.

The starting material or fresh feed to be converted, such as crude petroleum or a distillate, may be forced by valved connections through either or both of trimming coils 9b and 9a in the tops of fractionators 1b and 1a, respectively, for controlling the temperatures of the same, or may by-pass either or both of such coils, as desired, is conducted by line 10 through heat exchangers 10a and 10b in vapor lines 4a and 4b, respectively, of the two converting systems, and is admitted in a preheated condition, at 11, into fractionator 1b. Under some conditions of operation, additional cooling of vapors in fractionators 1b and 1a may be required and may be provided by the use of open reflux or other conventional means. A tray 12b in the upper portion of fractionator 1b makes an upper cut of the material therein, which is conducted by line 12a to serve as feed for heater 1a of catalytic system A. A lower tray 13b below fresh feed inlet 11 takes a bottom cut from the feed and heavy fractions of the converted streams, which cut is conducted by line 3c to serve as feed for heater 1c of viscosity breaker C. The portion of fractionator 1b below tray 13b forms a vaporizing zone 7b' into which line 4b of the pyrolytic system and line 2c of the viscosity breaker discharge, line 4b entering at a

point adjacent the bottom of the zone and line 2c discharging at a point intermediate the latter and tray 13b. Optionally, an additional tray 14b intermediate lower tray 13b and upper tray 12b 5 and above fresh feed inlet 11 may be provided to make an intermediate cut which is conducted by valved line 15b to connect with feed line 5b leading to heater 1b of the pyrolytic system. A valved control 16b is provided for line 15b such 10 that when line 15b is closed, the cut collected in tray 14b is drained into tray 13b by a branch 11b. The converted vapors escape from the top of fractionator 7b through a line 8b, to be condensed and stored or refined as desired. Tarry 15 residues are withdrawn from vaporizing zone 7b' through an outlet connection 18b. Heavy naphtha may be collected and withdrawn by a tray 19b near the top of fractionator 7b.

From the above, it will be apparent that the side 20 streams or cuts forming the feeds to the heater of the catalytic system and to the viscosity breaker are made in the fractionator 7b into which the preheated fresh feed and the products of the pyrolytic system and of the viscosity 25 breaker are discharged; that all the residual oil or recycle stock thrown down in fractionator 7a from catalytic system A is conducted to the heater of pyrolytic system B as feed therefor; that, optionally, a side stream or cut intermediate the 30 cuts for the catalytic system and for the viscosity breaker may be taken from fractionator 7b for the pyrolytic system, and that this cut may, if desired, be mingled with the residual oil from the catalytic system to make up the feed for the 35 pyrolytic system; and that when viscosity breaking device C is not used, tray 13b, which makes the cut therefor, will be omitted. The present arrangement is highly flexible, in that the viscosity breaker may be omitted, and that, if the 40 latter is not omitted, the intermediate cut for supplying a portion of the feed for the pyrolytic system from fractionator 7b may be omitted. In the latter case, the upper cut effected by tray 12b will be deep enough to pass a sufficient quantity 45 of material through catalytic system A to supply the required quantity of feed for the pyrolytic system B. This arrangement permits a selection of the relative capacities of the catalytic and pyrolytic systems. By making the intermediate 50 cut by tray 16b for the pyrolytic system B, however, the material fed to the catalytic system may be arranged to conform to that of the first or second pass of the catalytic system when operating normally, which passes give the best yields with 55 the least deposit of contaminants in the catalytic mass, and the entire apparatus may be adjusted to secure maximum conversion with a high octane rating. In particular, the arrangement provides a cracking stock for the pyrolytic system from 60 which it can make gasoline of high octane rating.

I claim as my invention:

1. The process of converting a high boiling composite hydrocarbon charge comprising components which are substantially higher boiling than 65 gasoline by catalytic and pyrolytic operations functioning interdependently and simultaneously and continuously which comprises separating said charge into at least two fractions of different boiling and molecular weight ranges, a lower boiling fraction and a higher boiling fraction, heating one of said fractions without substantial pyrolytic conversion thereof and passing it in vapor phase through a confined zone containing a solid adsorptive catalyst comprising activated hydrosilicate 70 of alumina so as to effect a transformation of 75

such fractions to a substantial extent into components within the gasoline boiling range, passing the other of said fractions through a second confined zone maintained under conditions capable of effecting a pyrolytic conversion thereof to a substantial extent into components within the gasoline boiling range, and blending hydrocarbons in the gasoline boiling range from products of reaction issuing from each of the said confined zones to form a commercial motor fuel. 10

2. The process of converting a high boiling composite hydrocarbon charge comprising components which are substantially higher boiling than gasoline by catalytic and pyrolytic operations functioning interdependently and simultaneously and continuously which comprises separating said charge into at least two fractions of different boiling and molecular weight ranges, a lower boiling fraction and a higher boiling fraction, heating one of said fractions without substantial pyrolytic conversion thereof and passing it in vapor phase through a confined zone containing a solid adsorptive catalyst comprising activated hydrosilicate of alumina so as to effect a transformation of such fraction to a substantial extent into components within the gasoline boiling range, passing the other of said fractions through a second confined zone maintained under conditions capable of effecting a pyrolytic conversion thereof to a substantial extent into components within the gasoline boiling range, and passing a portion of the higher boiling components of the product issuing from the first-mentioned confined zone, comprising hydrocarbons higher boiling than gasoline, into the said second confined zone together with the aforesaid other of said fractions of the hydrocarbon charge. 15

3. The process of converting a high boiling composite hydrocarbon charge comprising components which are substantially higher boiling than gasoline by catalytic and pyrolytic operations functioning interdependently and simultaneously and continuously which comprises separating said charge into at least two fractions of different boiling and molecular weight ranges, a lower boiling fraction and a higher boiling fraction, said lower boiling fraction being composed primarily of hydrocarbons substantially higher boiling than gasoline and within the gas oil boiling range and said higher boiling fraction being composed primarily of hydrocarbons higher boiling than the said lower boiling fraction, heating said lower boiling fraction without substantial pyrolytic conversion thereof and feeding it in vapor phase through a confined zone containing a solid adsorptive catalyst comprising activated hydrosilicate of alumina so as to effect a transformation of said lower boiling fraction to a substantial extent into components within the gasoline boiling range, passing the aforesaid higher boiling fraction through a second confined zone maintained under conditions capable of effecting a pyrolytic conversion of the same to a substantial extent into components within the gasoline boiling range, and blending hydrocarbons in the gasoline boiling range from products of reaction issuing from each of the said confined zones to form a commercial motor fuel. 40

4. A process of converting hydrocarbons by catalytic and pyrolytic means operating independently but simultaneously and continuously which comprises heating, vaporizing and separating the hydrocarbon starting material into a plurality of fractions in a fractionating zone, subjecting a light fraction having a higher boiling 45

range than gasoline to catalytic conversion, separating the products of the catalytic conversion into light hydrocarbons in the gasoline boiling range and a residual oil, subjecting a still higher boiling fraction from said fractionating zone with the residual oil from said catalytic conversion to pyrolytic conversion, and continuously fractionating the products of said pyrolytic conversion in said fractionating zone along with the hydrocarbon starting material into light hydrocarbons in the gasoline boiling range and into said plurality of fractions to secure said fractions higher boiling than gasoline.

5. A process of converting hydrocarbons by catalytic and pyrolytic means operating independently but simultaneously and continuously which comprises heating, vaporizing and separating the hydrocarbon starting material into a plurality of fractions in a fractionating zone, subjecting a light fraction having a higher boiling range than gasoline to catalytic conversion, separating the products of the catalytic conversion into light hydrocarbons in the gasoline boiling range and a residual oil, subjecting the residual oil from said catalytic conversion to pyrolytic conversion, heating a still higher boiling fraction from said fractionating zone to a moderate cracking temperature to break the viscosity of such fraction, and continuously fractionating the products of said pyrolytic conversion and of said viscosity breaking operation in said first named fractionating zone along with the hydrocarbon starting material into light hydrocarbons in the gasoline boiling range and into said plurality of fractions to secure said fractions higher boiling than gasoline.

6. A process of converting hydrocarbons by catalytic and pyrolytic means operating independently but simultaneously and continuously which comprises heating, vaporizing and separating the hydrocarbon starting material into a plurality of fractions in a fractionating zone, subjecting a light fraction having a higher boiling range than gasoline to catalytic conversion, separating the products of the catalytic conversion into light hydrocarbons in the gasoline boiling range and a residual oil, subjecting a still higher boiling fraction from said fractionating zone along with the residual oil from said catalytic conversion to pyrolytic conversion, heating a still higher boiling fraction from said fractionating zone to a moderate cracking temperature to break the viscosity of such fraction, and continuously fractionating the products of said pyrolytic conversion in said first named fractionating zone along with the hydrocarbon starting material into light hydrocarbons in the gasoline boiling range and into said plurality of fractions to secure said fractions higher boiling than gasoline.

7. Process of converting hydrocarbons by catalytic and pyrolytic operations functioning independently but simultaneously which comprises partly heating the hydrocarbon starting material, separating the starting material in a vaporizing and fractionating zone into at least five fractions, namely, a light fraction in the gasoline boiling range, a gas oil fraction, two heavier fractions, and a tarry residuum, heating the heaviest of these two heavier fractions to a moderate cracking temperature to break the viscosity of such fraction, separating the products of the viscosity breaking operation into fractions corresponding to those indicated above in the same fractionating zone and combining them with the

fractions from the continuously supplied hydrocarbon starting material, catalytically transforming the gas oil fraction, separating the products of the catalytic transformation into a light fraction in the gasoline boiling range and a residual oil, combining the residual oil with the first of said two heavier fractions, pyrolytically cracking said last named combined materials, separating the products of said pyrolytic cracking into five fractions corresponding to those indicated above in said same fractionating zone and combining them with the fractions from the continuously supplied hydrocarbon starting material and from the viscosity breaking operation, collecting the gasoline fractions from each of said separating steps as the desired low boiling products, and continuously performing the above steps.

8. The process of converting hydrocarbons which comprises heating, vaporizing and fractionating hydrocarbon starting material in a primary fractionating zone, withdrawing an overhead fraction from said zone in the gasoline boiling range, catalytically converting a higher boiling fraction at low pressure in the temperature range of 750° to 1000° F., fractionating the products of such conversion in a second fractionating zone to secure an overhead fraction in the gasoline boiling range and a residual oil, pyrolytically converting the residual oil from said second fractionating zone with the addition of a still higher boiling fraction from said primary fractionating zone, said pyrolytic conversion being effected under high pressure and within the temperature range of 850° to 1100° F., and fractionating the products of said pyrolytic conversion in said primary fractionating zone along with said starting material thereby to augment the volume of the fractions obtained therein.

9. The process of converting hydrocarbons which comprises heating, vaporizing and fractionating hydrocarbon starting material in a primary fractionating zone, withdrawing an overhead fraction from said zone in the gasoline boiling range, catalytically converting a higher boiling fraction at low pressure in the temperature range of 750° to 1000° F., fractionating the products of such conversion in a second fractionating zone to secure an overhead fraction in the gasoline boiling range and a residual oil, pyrolytically converting the residual oil from said second fractionating zone with the addition of a still higher boiling fraction from said primary fractionating zone, said pyrolytic conversion being effected under high pressure and within the temperature range of 850° to 1100° F., subjecting a still higher boiling fraction from said primary fractionating zone to a temperature in the range of 700° to 900° F. to break the viscosity of such fraction, and fractionating the products of said pyrolytic conversion and of said viscosity breaking operation in said primary fractionating zone along with said starting material thereby to augment the volume of the fractions obtained therein.

10. An apparatus for the production of low boiling hydrocarbons from high boiling hydrocarbons comprising means for heating hydrocarbons to conversion temperatures, alternate catalytic regenerative converters adapted to contain catalytic material, regenerative means, means for connecting the converters alternately to the hydrocarbon heating means and to the regenerative means, separate means for heating hydrocarbons to pyrolytic conversion temperatures, a time reaction chamber, means connecting the separate

- pyrolytic heating means to the chamber, independent means for heating hydrocarbons to a moderate cracking temperature to reduce their viscosity, a fractionating column, a bottom off-
take means on said column, means connecting the catalytic converters to said fractionating column, a second vaporizing and fractionating column, means connecting the time reaction chamber to the second column, means connecting the independent heating means to said second column, means for introducing charge oil into the second column, upper and lower offtakes from said second column, means connecting the upper offtake to said first heating means, means connecting the lower offtake to said independent heating means, means connecting the bottom offtake of the first column to the separate pyrolytic heating means, and vapor removing means connected to the first and second columns.
13. An apparatus for the production of low boiling hydrocarbons from high boiling hydrocarbons comprising means for heating hydrocarbons to conversion temperatures, alternate catalytic regenerative converters adapted to contain catalytic material, regenerative means, means for connecting the converters alternately to the hydrocarbon heating means and to the regenerative means, separate means for heating hydrocarbons to pyrolytic conversion temperatures, a time reaction chamber, means connecting the separate pyrolytic heating means to the chamber, independent means for heating hydrocarbons to a moderate cracking temperature to reduce their viscosity, a fractionating column, a bottom offtake means on said column, means connecting the catalytic converters to said fractionating column, a second vaporizing and fractionating column, means connecting the time reaction chamber to the second column, means connecting the independent heating means to said second column, means for introducing charge oil into the second column, upper and lower offtakes from said second column, means connecting the upper offtake to said first heating means, means connecting the lower offtake to said independent heating means, means connecting the bottom offtake of the first column to the separate pyrolytic heating means, and vapor removing means connected to the first and second columns, said charge oil means entering said second column between said upper and lower offtakes and said connecting means from said time reaction chamber and from said viscosity breaking means entering said second column below said lower offtake.
14. An apparatus for the production of low boiling hydrocarbons from high boiling hydrocarbons comprising means for heating hydrocarbons to conversion temperatures, alternate catalytic regenerative converters adapted to contain catalytic material, regenerative means, means for connecting the converters alternately to the hydrocarbon heating means and to the regenerative means, separate means for heating hydrocarbons to pyrolytic conversion temperatures, a time reaction chamber, means connecting the separate pyrolytic heating means to the chamber, a fractionating column, bottom offtake means on said column, means connecting the catalytic converters to said fractionating column, a second vaporizing and fractionating column, means connecting the time reaction chamber to the second column, means for introducing charge oil into said second column, an offtake from said second column, means connecting said offtake to said first heating means, means connecting the bottom offtake of the first column to said separate pyrolytic heating means, and vapor removing means connected to said first and second columns, said charge oil means entering said second column below said offtake and said connecting means from said time reaction chamber entering said second column below said charge oil means.
15. An apparatus for the production of low boiling hydrocarbons from high boiling hydrocarbons comprising means for heating hydrocarbons to conversion temperatures, alternate catalytic regenerative converters adapted to contain catalytic material, regenerative means, means for connecting the converters alternately to the hydrocarbon heating means and to the regenerative means, separate means for heating hydrocarbons to pyrolytic conversion temperatures, a time reaction chamber, means connecting the separate pyrolytic heating means to the chamber, a fractionating column, bottom offtake means on said column, means connecting the catalytic converters to said fractionating column, a second vaporizing and fractionating column, means connecting the time reaction chamber to the second column, means for introducing charge oil into said second column, upper and lower offtakes from said second column, means connecting the upper offtake to said first heating means, means connecting the bottom offtake of the first column to said separate pyrolytic heating means, and vapor removing means connected to said first and second columns, said charge oil means entering said second column below said offtake and said connecting means from said time reaction chamber entering said second column below said charge oil means.

drocarbon heating means and to the regenerative means, separate means for heating hydrocarbons to pyrolytic conversion temperatures, a time reaction chamber, means connecting the separate pyrolytic heating means to the chamber, independent means for heating hydrocarbons to a moderate cracking temperature to reduce their viscosity, a fractionating column, a bottom offtake means on said column, means connecting the catalytic converters to said fractionating column, a second vaporizing and fractionating column, means connecting the time reaction chamber to the second column, means connecting the independent heating means to said second column, means for introducing charge oil into the second column, upper, lower and intermediate offtakes from said second column, means connecting the upper offtake to said first heating means, means connecting the lower offtake to said independent heating means, means connecting the bottom offtake of the first column to the separate pyrolytic heating means, a valved connection from said intermediate offtake to said separate pyrolytic heating means, and vapor removing means connected to said first and second columns, said charge oil means entering said second column between said lower and intermediate offtakes and said connecting means from said time reaction chamber and from said viscosity breaking means entering said second column below said lower offtake.

16. An apparatus for the production of low boiling hydrocarbons from high boiling hydrocarbons comprising means for heating hydrocarbons to conversion temperatures, alternate catalytic regenerative converters adapted to contain catalytic material, regenerative means, means for connecting the converters alternately to the hydrocarbon heating means and to the regenerative means, separate means for heating hydrocarbons to pyrolytic conversion temperatures, a time reaction chamber, means connecting the separate pyrolytic heating means to the chamber, a fractionating column, a bottom offtake means on said column, means connecting the catalytic converters to said fractionating column, a second vaporizing and fractionating column, means connecting the time reaction chamber to the second column, means for introducing charge oil into said second column, upper and lower offtakes from said second column, means connecting the upper offtake to said first heating means, means connecting the bottom offtake of the first column to said separate pyrolytic heating means, a valved connection from said lower offtake to said last named heating means, and vapor removing means connected to said first and second columns, said charge oil means entering said second column below said lower offtake and said connecting means from said time reaction chamber entering said second column below said charge oil means.

17. An apparatus for the production of low boiling hydrocarbons from high boiling hydrocarbons comprising means for heating hydrocarbons to conversion temperatures, alternate catalytic regenerative converters adapted to contain catalytic material, regenerative means, means for connecting the converters alternately to the hydrocarbon heating means and to the

regenerative means, separate means for heating hydrocarbons to pyrolytic conversion temperatures, a time reaction chamber, means connecting the separate pyrolytic heating means to the chamber, independent means for heating hydrocarbons to a moderate cracking temperature to reduce their viscosity, a fractionating column, a bottom offtake means on said column, means connecting the catalytic converters to said fractionating column, a second vaporizing and fractionating column, means connecting the time reaction chamber to the second column, means connecting the independent heating means to said second column, means for introducing charge oil into the second column, upper and lower offtakes from said second column, means connecting the upper offtake to said first heating means, means connecting the lower offtake to said independent heating means, means connecting the bottom offtake of the first column to the separate pyrolytic heating means, and vapor removing means connected to the first and second columns, said connecting means from said viscosity breaking means entering said second column adjacent the bottom thereof while said connecting means from said time reaction chamber and said charge oil means enter said second column at successively higher levels.

18. An apparatus for the production of low boiling hydrocarbons from high boiling hydrocarbons comprising means for heating hydrocarbons to conversion temperatures, alternate catalytic converters adapted to contain catalytic material, regenerative means, means for connecting the converters alternately to the hydrocarbon heating means and to the regenerative means, separate means for heating hydrocarbons to pyrolytic conversion temperatures, a time reaction chamber, means connecting the separate pyrolytic heating means to the chamber, independent means for heating hydrocarbons to a moderate cracking temperature to reduce their viscosity, a fractionating column, a bottom offtake means on said column, means connecting the catalytic converters to said fractionating column, a second vaporizing and fractionating column, means connecting the time reaction chamber to the second column, means connecting the independent heating means to said second column, means for introducing charge oil into the second column, upper, lower and intermediate offtakes from said second column, means connecting the upper offtake to said first heating means, means connecting the lower offtake to said independent heating means, means connecting the bottom offtake of the first column to the separate pyrolytic heating means, a valved connection from said intermediate offtake to said separate pyrolytic heating means, and vapor removing means connected to said first and second columns, said connecting means from said viscosity breaking means entering said second column adjacent the bottom of the latter, while said connecting means from said time reaction chamber enters said second column somewhat above said viscosity breaking connection but below said lower offtake, while said charge oil means enters said second column above said lower offtake.

HOWARD W. SHELDON. 70
